Eleanor A. Mehr, 317 E. 145th St., Harvey, Ill.

Filed Mar. 14, 1961, Ser. No. 64,287

Term of patent 14 years

(Cl. D7—5)

FIGURE 6 is a side view of the heel as it appears when assembled to a shoe, the dotted line fragmentary showing of the shoe being for illustrative purposes only.

I claim:

The ornamental design for a lady's shoe heel, as shown and described.
